MATERIAL LOADING DEVICE

Fritz Johnson, Idaho Falls, Idaho

Application June 25, 1943, Serial No. 492,280

6 Claims. (Cl. 214—140)

This invention relates to material loading devices and more particularly to a device for loading manure or other material.

An object of this invention is to provide a loading device wherein the scoop or bucket is maintained in horizontal position while being elevated from a lower filling position to an upper discharging position.

Another object of this invention is to provide a device of this kind which can be readily mounted as an attachment on a tractor.

A further object of this invention is to provide in a device of this kind an improved latching means for holding the loaded scoop while the latter is being elevated and releasing the same for discharge of the contents.

A further object of this invention is to provide, in a device of this kind, an improved pivotal mounting for the scoop which includes spring means for automatically returning the scoop to a horizontal position when the contents have been discharged and automatically latching the scoop in the horizontal position.

A further object of this invention is to provide an improved means for maintaining the horizontal position of the scoop while the latter is being elevated or lowered.

With the foregoing objects in view and others which may hereinafter more fully appear the invention consists of the novel construction, combination and arrangement of parts as will be more specifically described, and illustrated in the accompanying drawings wherein are shown embodiments of the invention, but it is to be understood that changes, variations and modifications may be resorted to which fall within the scope of the invention as claimed.

In the drawings:

Figure 1 is a detail side elevation of a material loading attachment constructed according to an embodiment of this invention, mounted on a tractor;

Figure 2 is a plan view of the device;

Figure 3 is a detail front elevation of the support for the elevator;

Figure 4 is a fragmentary side elevation of the forward portion of the elevator;

Figure 5 is a fragmentary side elevation of the latching means for the scoop;

Figure 6 is a fragmentary plan view, partly in section, of the scoop holding and releasing bars; and

Figure 7 is a sectional view taken on the line 7—7 of Figure 5.

Referring to the drawings the numeral 10 des-

ignates generally a tractor which includes a frame 11 and a power take-off 12 at the rear of the frame 11. A scoop 14 is swingably mounted on the forward end of the tractor 10 being 5 swingably or pivotally carried by a pair of elongated levers 15. The levers 15 are, in the present instance, formed of channel bars and are disposed one on each side of the frame 11 and pivotally mounted at their rear ends on pivot members 16 which are carried by a depending plate 17 which is fixed to the frame 11 between the ends of the latter. The scoop 14 comprises a plurality of spaced apart parallel L-shaped bars 18 which are round in transverse section and 10 which are connected together on one side thereof by a connecting bar 19 which may be welded or otherwise firmly secured to the lower sides of the bars 18. The bars 18 have vertical rear sides 20 which constitute the back wall of the scoop 14 and the outer ends of the vertical sides 20 are 15 connected together by means of an angle bar 21 which may be welded or otherwise firmly secured to the upper ends of the vertical sides 20. A pair of side angularly disposed bracing plates 22 are 20 secured to the bottom sides of the L-shaped bars 18, and extend upwardly and rearwardly and are secured as by welding or the like to the outermost of the vertical rear sides 20 and are also secured as by welding or the like to the angle bar 25 25 30 35 40 45 50 55 60 65 70 75 80 85 90 95 100 105 110 115 120 125 130 135 140 145 150 155 secured as at 34 to the outer side of the tractor frame 11, rearwardly of the forward end of the latter. The lower transverse connecting bar 38 is adapted to be secured in any suitable manner to the forward end of the tractor frame 11. The upper transverse connecting bar 35 is secured between the upper ends of the uprights 28 and a pair of sheaves 36 are secured in upstanding relation to the upper connecting bar 35.

A pair of cables 37 have one end thereof secured, as at 38, to the upper connecting bar 35 of the frame 28, and are then trained through the sheaves 26 and the sheaves 36 and then extended downwardly and pass through a lower pair of sheaves 39 which are fixed to the opposite sides of the frame 11 rearwardly of the upright frame 28. The cables 37 are then extended rearwardly beneath the frame 11 and wound about the winding drum 25.

In order to provide a means whereby the scoop 14 may be releasably held in substantial horizontal position when in either a lower or an elevated position, I have provided a holding means, generally designated as 40. The holding means 40 comprises a pair of elongated bars 41 and 42 which are disposed in face-abutting relation and the bar 42, at its rear end, is formed with a fork 43. An upright bar 44 is pivotally mounted on a pivot 45, carried by an upstanding lug 46 which is fixed to the upper side of a lever 15 adjacent the rear end of the latter. There are two of these latching means 40, one on each side of the frame 11, and the fork 43 is formed with a plurality of openings 47 through a selected one of which a pivot pin 48 is adapted to engage. The pin 48 also engages through a selected one of a plurality of openings 49 which are formed in the upright bar 44. The bar 44 is held in substantially upright position in any position of the levers 15 by means of an arcuate holding bar 50. The bar 50 is pivotally secured as at 51 to the upright bar 44 and is also pivotally secured as at 52 to the frame 11.

The bar 41 comprises an endwise movable bar which is formed with a guide 53 between the ends thereof which slidably engages about the bar 40. The bar 42 is also formed, adjacent the forward end thereof, with a looped guide 54 through which the bar 41 is slidable. A stop lug 55 is fixed to the outer side of the bar 40 and is adapted to be engaged by the guide 53 when the slide bar 41 is in its foremost position. The forward end of the sliding bar 41 is provided with a fork 56 and an L-shaped member 57 is secured to the outer side of each side plate 22, and has the rearwardly extending side 58 thereof disposed between the arms of the fork 56 and pivotally secured by means of a bolt or pivot member 59. The sliding bar 41 is releasably latched with respect to the bar 42 by means of a U-shaped keeper 60 which is pivotally mounted as at 61 on a downwardly extending lug 62 carried by the rear portion of the bar 41. The U-shaped keeper 60 extends over the two bars 41 and 42 and is adapted to releasably engage a triangularly shaped lug 63 which is fixed to the upper side of the bar 42. The two keepers 60 are connected together by means of a connecting bar 64 and the handle 65 is secured to the central portion of the connecting bar 64. The connecting bar 64 is of U-shaped construction and is disposed at an obtuse angle to the keepers 60 so as to be overbalanced toward the rear in order that the two keepers 60 will gravitantly swing downwardly to a locking position. The two keepers are yield-

ably held in a latched position by means of a spring-pressed bar 66. The bar 66 is threaded through an outstanding lug 67 carried by the forward portion of the bar 41, and the bar or rod 66 is slidable through a pair of guide lugs 68 carried by the bar 42. A stop pin 69 is extended through the rear portion of the rod 66 to thereby limit the forward sliding movement of the rod 66 through the guides 68.

A spring 70 is disposed about the rod 66, bearing at its rear end against the foremost one of the pair of guide lugs 68 and also bearing against a washer or plate 71 carried by the rod 66. The rod 66 is locked in its adjusted position with respect to the lug 67 by means of a pair of lock nuts 72.

The bucket 14 is constantly urged to a discharging or dumping position by means of a pair of springs 73 which are mounted on a pair of rods 74 carried by the side members 22. The rods 74 extend rearwardly of the bucket 14, being secured at their forward ends in outstanding lugs 75 which are held by the said members 22. A washer 76 is fixed in longitudinally adjusted position on the rod 74 by means of a pin or stop member 77. The rear end of the spring 73 is adapted to engage an upstanding arcuate plate 78 which is carried by a base 79 fixed to the upper side of the connecting bar 27. The plate 78 has the convex side thereof foremost and is formed with an opening 80 through which the rod 74 is adapted to slidably and rockably engage. The springs 73, upon release of the latching members or keepers 60, are adapted to rock the bucket 14 forwardly and downwardly to its discharging position. When the bucket 14 rocks downwardly the two rods 74 are moved forwardly and a second pair of springs 81 are mounted on the rods 74 rearwardly of the plates 78. The springs 81, at their forward ends, bear against washers 82 which are slidably mounted on the rods 74. The rear ends of the springs 81 bear against rear washers 83 which are secured against rearward movement by stop pins 84. The two springs 81 are adapted to be compressed when the bucket 14, in its filled condition, is rocked forwardly and downwardly and the springs 81 are of such strength that when the bucket 14 is emptied the springs 81 will yieldingly swing the bucket 14 upwardly to a substantially horizontal position at which time the keepers 60 will drop behind the locking lugs 63 carried by the bars 42.

In the use and operation of this loading attachment the frame 28 is secured to the frame 11 of the tractor, and the levers 15 are pivotally secured to the shaft or pivot member 16. The cables 37 are wound about the drum 25 which is connected to the power take-off 12 and when the scoop or bucket 14 is to be loaded it is lowered to the dotted line position shown in Figure 1. The tractor 10 is then moved forwardly and when the scoop or bucket 14 is filled, the drum 25 is rotated to raise the levers 15 to the full line position shown in Figure 1. The tractor 10 may then be moved forwardly to the desired location and upon forward and upward rocking of the handle 65 and the U-shaped connector 64, the two keepers 60 will be released thereby permitting the keepers 60, with the sliding bar 41, to move forwardly under the tension of the springs 73. The springs 73 will rock the scoop or bucket 14 downwardly to a discharging position and when the scoop has been emptied the springs 81, which at this time are under tension, will rock the bucket rearwardly and upwardly to dispose the bot-

tom thereof in a horizontal position. When the bucket 14 rocks upwardly and rearwardly to a horizontal position the keepers 60 will slide over the upper obtuse sides of the locking lugs 62, and the keepers 60 will then gravitantly drop down against the rear ends of the locking lugs 62. When the sliding bar 41 is in its rearmost position the spring 70 will be under tension so that the two keepers 60 will be yieldingly held in their locked position.

The scoop 14 is preferably so mounted as to be overbalanced to the rear when it is empty. When the filled scoop 14 is to be discharged the keepers 60 will be released, and at this time springs 73 will assist in rocking the scoop 14 forwardly and downwardly past the center of gravity to a discharged position. When the scoop 14 is in discharging position springs 81 will be under tension and as soon as the scoop 14 has emptied, springs 81 will rock the scoop upwardly and rearwardly past the center of gravity. During the latter rocking of the empty scoop 14, and at the time the keepers 60 are riding over the lugs 62 springs 73 will cushion the movement of the scoop, while springs 70 will also cushion the sliding movement of bar 41. The cushioning of the movement of the scoop is desired for the purpose of retarding its movement because the scoop is overbalance in a substantial amount toward the rear, so that the cushioning spring will relieve the structure of excessive jars while at the same time assisting in discharging the scoop.

I claim:

1. A loading attachment for a tractor comprising a scoop, levers swingably mounting said scoop on the frame of the tractor, releasable latching means carried by said levers and connected with said scoop and the tractor frame for maintaining said scoop in a horizontal position, means for raising or lowering said levers, said latching means including means under tension when said scoop is in a horizontal position constantly urging said scoop to a discharging position, said latter means upon release of said latching means automatically swinging said scoop to discharging position, and means operable upon swinging of said scoop to discharging position for automatically returning the scoop to latched position.

2. A loading attachment for a tractor comprising a scoop, levers swingably mounting said scoop on the frame of the tractor, releasable latching means carried by said levers and connected with said scoop and the tractor frame for maintaining said scoop in a horizontal position, and means for raising or lowering said levers, said latching means including spring means constantly urging said scoop to a discharging position, and a second spring means tensionable when said scoop is moved to a discharging position by said first spring means for automatically returning said scoop to a horizontal latched position when said scoop is empty.

3. A loading attachment for a tractor comprising a pair of scoop supporting levers, means pivotally mounting the rear ends of said levers on the tractor frame, a scoop between the forward ends of said levers, releasable means carried by said levers connected to said scoop and the tractor frame for holding said scoop horizontal, and means for raising or lowering said levers, said releasable means including pairs of elongated bars, means slidably connecting the bars of each pair to said scoop, a pair of upright bars pivot-

ally carried by said levers adjacent the rear ends of the latter, means pivotally connecting the upper portion of each upright bar to the other of said pair of elongated bars, means connected to said upright bars and to the tractor frame for holding said upright bars substantially vertical in any position of said levers, a locking lug carried by said other bar of each pair of elongated bars, and a pivoted keeper carried by said one bar of each pair of elongated bars engageable with said locking lug for releasably holding said one bar against endwise movement relative to said other bar.

4. A loading attachment for a tractor comprising a pair of scoop supporting levers, means pivotally mounting the rear ends of said levers on the tractor frame, a scoop between the forward ends of said levers, releasable means carried by said levers connected to said scoop and the tractor frame for holding said scoop horizontal, and means for raising and lowering said levers, said releasable means including pairs of elongated bars, means slidably connecting the bars of each pair to said scoop, a pair of upright bars pivotally carried by said levers adjacent the rear ends of the latter, means pivotally connecting the upper portion of each upright bar to the other of said pair of elongated bars, means connected to said upright bars and to the tractor frame for holding said upright bars substantially vertical in any position of said levers, a locking lug carried by said other bar of each pair of elongated bars, and a pivoted keeper carried by said one bar of each pair of elongated bars engageable with said locking lug for releasably holding said one bar against endwise movement relative to said other bar, and tensionable means for holding said keeper in lug-engaging position.

5. A loading attachment for a tractor comprising an upright frame, means securing said frame to the frame of the tractor, a pair of elongated levers, means pivotally securing the rear ends of said levers to the tractor frame, a scoop pivotally carried by the forward ends of said levers, a pair of elongated latched bars for each lever, means pivotally securing one bar to said scoop, an upright bar pivotally carried by each lever, means secured to the tractor frame for holding said upright bar vertical in any position of said levers, means securing the other bar of each pair to said upright bar, means slidably securing said elongated bars together, correlated means for releasably latching said elongated bars together, and means for raising or lowering said levers, said elongated bars normally maintaining said scoop horizontal in any position of said levers, spring means tensioned when said scoop is in a horizontal position constantly urging the scoop to discharging position, and a second spring means tensioned upon swinging of the scoop to discharged position for returning the scoop to horizontal position.

6. A loading attachment for a tractor including a scoop adapted to be held in horizontal position while being elevated from the lower filling position to an upper discharging position, a latching means for holding the loaded scoop, and releasing means for the discharge of the contents of said scoop, a pivotal mounting for the scoop including spring means for automatically returning the scoop to a horizontal position when the contents have been dumped, and automatically latching the scoop in horizontal position.
